CLAIM

The ornamental design for a glass hummingbird feeder, as shown and described.

DESCRIPTION

FIG. 1 is a front elevational view of a glass hummingbird feeder showing my design;
FIG. 2 is a rear elevational view thereof;
FIG. 3 is a left side view thereof;
FIG. 4 is a right side view thereof;
FIG. 5 is a top plan view thereof; and,
FIG. 6 is a bottom plan view thereof.
